SPLIT TUBE CIGARETTE SNUFFER

John F. Smillie, San Diego, Calif.

Application December 15, 1952, Serial No. 326,076

6 Claims. (Cl. 131—235)

The present invention relates generally to a cigarette snuffer and more particularly to a split tube cigarette snuffer.

The primary object of this invention is to provide a split tube cigarette snuffer which will quickly extinguish a cigarette placed in the tube, without damaging the cigarette so that it may be relighted if desired.

Another object of this invention is to provide a cigarette snuffer which will extinguish a cigarette without crushing, thus preventing soiling of the fingers.

Another object of this invention is to provide a cigarette snuffer comprising a split tube which may be opened by direct means to release an extinguished cigarette.

Another object of this invention is to provide a split tube cigarette snuffer having an angularly disposed hinge, whereby the lower end portions of said split tube become more widely separated than the upper end portions to provide sure release of the extinguished cigarette.

With these and other objects in view, this invention consists in the novel construction, combination and arrangement of elements and portions, as will be herein-after fully described in the specification, particularly pointed out in the claims, and illustrated in the drawing which forms a material part of this disclosure and wherein similar characters of reference indicate similar or identical elements and portions throughout the specification and throughout the views of the drawing, and in which:

Fig. 1 is a vertical sectional view of an automobile type ash tray with the split tube cigarette snuffer shown in elevation.

Fig. 2 is a partial sectional view taken on the line 2—2 of the ash tray shown in Fig. 1, the cigarette being omitted.

Fig. 3 is a partial sectional view taken on the line 3—3 of the ash tray shown in Fig. 1.

Fig. 4 is a central vertical sectional view of the cigarette snuffer of the ash tray shown in Fig. 1.

Fig. 5 is a front elevation view of the cigarette snuffer.

Fig. 6 is a front elevation view of the cigarette snuffer with the split tube in the open position.

Referring now to the drawing in detail, the device is shown installed in an automobile type ash tray 10 having a support arm 12 which has an attachment lug portion at the lower end thereof riveted to the ash tray and the arm is provided with a roller 14.

The cigarette snuffer includes a bracket 16 secured to an end portion of the support arm 12, said bracket having an upper tab 18 and a lower tab 20 which act as supports for a hinge pin 22. The split tube 24 comprises two generally semi-cylindrical half tubes or sections 26 to which are secured the hinge leaves 28, each of said hinge leaves having a pair of inwardly disposed lugs 30 through which passes the hinge pin 22. It should be noted that the hinge leaves 28 are shaped so that the split-tube 24 is angularly disposed in relation to the hinge pin 22 for reasons which will later be explained. The half tubes or sections 26 are retained in a closed

2

position by means of a spring 32 which is arranged coaxially of the hinge pin 22, the ends of said spring engaging the outside surfaces of the hinge leaves 28 so as to bias the half tubes toward each other.

5 The split tube 24 comprises a tapered portion 34, the smallest diameter being at the lower end, while the upper end is provided with an outwardly flared mouth 36 to permit the easy insertion of a cigarette stub 38 as illustrated in Fig. 4.

10 The split tube 24 is held in a vertical plane including the axis of the hinge pin 22 by means of a tongue 40, welded as indicated at 41 in Figure 1, or otherwise secured to the lower tab 20, said tongue projecting upwardly between the hinge leaves 28 and being laterally engaged by the same when the half tubes 26 are in the closed position.

The split tube may be manually opened by means of the arms 42 which are secured to the half tubes 26 at the upper edge of the flared mouth 36. The arms 42 overlap and project outwardly from the split tube 24, each of said arms having thereon a knob 44. When the arms 42 are pressed together as illustrated in Fig. 6, the half tubes 26 will be forced apart so releasing any cigarette stub contained therein. Due to the fact that the axis of the hinge is angularly disposed with reference to the axis of the split tube and to the vertical, the half tubes 26 will open further apart at their lower ends than at their upper ends, so providing positive release of cigarette stubs. The opening movement of the half tubes 26 is equalized by a stop plate 46 welded to, or otherwise secured in fixed relation relative to the bracket 16, said stop plate having arcuate recessed edge 48 which receives the half tubes 26 in the open position as illustrated in Fig. 2.

25 35 The split tube 24 is best made of metal so that the heat of a cigarette stub inserted therein will quickly be dissipated. This rapid dissipation of heat, plus the fact that air currents are precluded, results in the cigarette stub being extinguished. It has been found in practice that the action is very fast, requiring but a few seconds to extinguish a cigarette, after which time the stub may be dropped into the ash tray by opening the split tube as described above.

40 45 It will be obvious that the cigarette snuffer described herein is not restricted to installation in automobile type ash trays, but may be used with other ash trays and with a wide variety of snuffer supporting means.

It is understood that minor variation from the form 50 55 of the invention disclosed herein may be made without departure from the spirit and scope of the invention, and that the specification and drawing are to be considered as merely illustrative rather than limiting.

I claim:

55 1. A cigarette snuffer comprising a supporting bracket, a split tube having complementary sections, a hinge pivotally attaching said complementary sections to said bracket, means for pivotally separating said sections, the axis of said hinge being angularly disposed relative to the vertical as well as to the axis of said split tube and said axes converging toward a point above said split tube, whereby the lower ends of said complementary sections are more widely separated than the upper ends when said means is operated.

60 65 2. A cigarette snuffer comprising a supporting bracket, a split tube having complementary sections, a hinge pivotally attaching said complementary sections to said bracket, means for pivotally separating said sections, the axis of said hinge being angularly disposed relative to the vertical as well as to the axis of said split tube and said axes converging toward a point above said split tube, whereby the lower ends of said complementary sections 70 are more widely separated than the upper ends when

3

said means is operated, and a spring operatively mounted on said hinge and biasing said complementary sections toward each other.

3. A cigarette snuffer comprising a supporting bracket, a split tube having complementary sections, a hinge pivotally attaching said complementary sections to said bracket, means for pivotally separating said sections, the axis of said hinge being angularly disposed relative to the vertical as well as to the axis of said split tube and said axes converging toward a point above said split tube, whereby the lower ends of said complementary sections are more widely separated than the upper ends when said means is operated, said hinge having a hinge pin and hinge leaves secured individually to said sections, and a spring coiled around said hinge, the ends of said spring engaging said hinge leaves whereby said complementary sections are biased toward each other, said means for separating including arms secured to said hinge leaves, said arms overlapping and extending outwardly from said split tube from the side thereof remote from said hinge, said arms having terminals remote from said sections and said terminals comprising manual engagement members which can be pressed toward each other to cause the sections to separate.

4. A cigarette snuffer comprising a supporting bracket, a split tube having complementary sections, a hinge having a pin pivotally attaching said complementary sections to said bracket, means for pivotally separating said sections, the axis of said hinge pin being angularly disposed relative to the vertical as well as to the axis of said split tube and said axes converging toward a point above said split tube, whereby the lower ends of said complementary sections are more widely separated than the upper ends when said means is operated, a

4

spring coiled around said hinge pin, the ends of said spring engaging said complementary sections whereby said complementary sections are biased toward each other, said separating means including arms secured to

5 said complementary sections, said complementary sections each comprising a slightly tapered, semi-frusto-conical lower portion, an outwardly flared upper portion, and an extended upwardly tapering hinge portion.

5. A cigarette snuffer according to claim 4 and including a tongue, said complementary sections being retained in symmetrical disposition with reference to a vertical plane through said hinge pin and tongue by means of said tongue, said tongue being fixedly secured to said bracket and disposed between said extended hinge portions.

6. A cigarette snuffer according to claim 4 including
